UNITED STATES PATENT OFFICE.

MARION B. RIFFO, OF PHILADELPHIA, PENNSYLVANIA.

PNEUMATIC-SERVICE CARRIER.

No. 853,936.

Specification of Letters Patent.

Patented May 14, 1907.

Original application filed December 18, 1905, Serial No. 292,396. Divided and this application filed October 13, 1906.
Serial No. 338,729.

To all whom it may concern:

Be it known that I, MARION B. RIFFO, a citizen of the United States, residing in the city of Philadelphia, State of Pennsylvania, have invented certain new and useful Improvements in Pneumatic-Service Carriers, of which the following is a full, clear, and exact description, reference being had to the accompanying drawings, forming a part of this specification.

My invention relates to carriers for use in despatch tubes in pneumatically-operated service system, and has for its object to provide means operating as well to limit the relative rotation of the telescoping tubular members of the carrier as also to maintain them in operative relation by preventing their accidental endwise dissociation in driving the carrier through the despatch tubes; the means provided, and their specific combination and arrangement, also permitting easy separation of the members for repair or replacement of parts when worn out.

To attain these objects my invention consists of the combination and arrangement of elements, hereinafter described, to perform the functions stated, my present application being a division of a pending and allowed application Serial No. 292,396, filed December 18, 1905.

In the drawings hereto annexed, in which the same letters of reference indicate like parts in the several views:—Figure 1 is a longitudinal sectional view of my new carrier; Fig. 2 is a transverse section on line 2—2 of Fig. 1; Fig. 3 is a transverse section on line 3—3 of Fig. 1, and Fig. 4 is a like view of a modified form, in that the stop-mechanism on the co-acting members of Fig. 3, are reversed.

In pneumatic service carriers as commonly constructed, the essential elements are a pair of cylindrical tubes, each having a closed head end and an open end, the tubes being assembled sleeve-like, that is to say, telescoping, the open end of each tube brought to bear, directly or indirectly, against the headend of the other tube, both tubes being peripherally slotted longitudinally, said slots being adapted to register on the relative rotation of the tubes one within the other, and with means to limit the rotation, consisting usually of an outwardly projecting lug on the inner tube and a recessed transverse extension of the peripheral slot in the outer tube.

These devices are necessarily subjected to hard wear, tending to separate the tubes, by a springing of the outer tubular body, which wholly destroys their usefulness, and moreover the combination referred to prevents easy repair of parts.

In my device hereinafter described, the tubular members are constructed as heretofore save for the modification of the open end of the inner tube as hereinafter described, but the means for operatively uniting them and limiting their relative rotation, are different, are new and of my invention, and these I will now describe.

The outer tubular member (Figs. 1 to 4) is indicated at 2, and is a cylindrical hollow tube having a head end 3 shown integral therewith, the opposite end being open. It is peripherally slotted, longitudinally, at 4. The inner tube 5 is similarly constructed, indicating its closed head end, but its opposite open end has an inwardly projecting flange 25. These tubes are assembled by bringing the open end of the outer tube 2 over the open end of the inner tube 5 in a sleeve-like manner, the tubes fitting each other reasonably close and adapted to rotate relatively, one within the other, so that the peripheral openings or slots 4 in the tubes may, by such relative rotation, be brought into register or thrown out of coincidence, to open or close the carrier.

Fitting tightly over the headend 6 of the inner tube 5 is a strengthening and closing plate 20 disk-like in form, and having an inwardly projecting annular flange 21 alining with and abutting against the open end of the outer tube 2; this plate 20 being securely fastened to said head end 6 of the inner tube by a rivet 10, and both of them fastened by removable screw bolts 9 to the buffer head 11 by means of the inset blocks 22 and 23 therein.

Fitting tightly within the inner tube 5, at its open end, is a disk-like closing plate 7, serving to hold the several parts, when assembled as hereinafter stated, from normal longitudinal separation. This plate 7 is preferably supplied with a short annular flange 17, projecting inwardly. This disk 7 rests against the face of the inturned flange 25 on the open end of the inner tubular member 5; and that flange in turn rests against the head end 3 of the outer tube. The flange 25 is therefore between the closing disk 7 and

the headend 3 of the outer tube, as shown in Fig. 1. This flange 25 forms one element of a co-acting stop mechanism, the other element of which is a disk 29 of slightly smaller 5 diameter, which also is interposed between the closing disk 7 and the headend 3 of the outer tubular member, and it so rests within the open end of the inner tubular member and in alinement with the annular flange 25 10 on said open end of the inner tube. Said closing disk 7, said inner disk 29 and the headend 3 of the outer tubular member, are securely fastened together by a rivet 10, and all of them as a whole fastened by removable 15 screw-bolts 9 to the buffer head 11. Thus it is seen that the closing disk 7, the inner disk 29 and the outer tubular member 2, being fastened together, will always rotate together 20 relatively to the inner tubular member 5, the inturned flange 25 of which will rotate around the relatively fixed inner disk 29 and in the same vertical plane therewith. The stop mechanism is provided between the coinciding peripheral edges of said flange 25 and 25 of said disk 29, and consists of a segmental recess on one of them with a co-acting tooth on the other. In Fig. 3, the inner fixed disk 29 has its peripheral edge cut away for a segmental distance to allow a partial rotation 30 only of the coinciding flange 7 of the inner tubular member which carries a stop tooth 28 projecting into such segmental recess. In Fig. 4 I have shown the reverse arrangement of these co-acting stop elements, in which the 35 tooth stop 28 is on the inner fixed disk 29 and the segmental recess is on the inturned flange 25 of the inner tubular member.

Having thus described my invention, I claim as new and desire to secure by Letters 40 Patent:—

1. A carrier for pneumatic service systems consisting of a pair of cylindrical tubular

members arranged relatively rotatable and peripherally slotted, each provided with a closed head end and an open end, means to 45 maintain said tubes from relative longitudinal movement, the inner of said tubular members having at its open end an inturned annular flange, a disk smaller than said annular flange fixedly secured to the interior 50 face of the head end of the outer tubular member, with a projecting stop and co-acting segmental recess between the coinciding peripheries of said disk and flange operating to limit the relative rotation of said tubular 55 members.

2. A carrier of the class recited comprising a pair of telescoping and relatively rotatable cylindrical tubular members, peripherally slotted, each with a head end and an open 60 end, a cap over the head end of the inner member, means to fasten them together and to a buffer head, in combination with means to limit the relative rotation of said tubular members, consisting of an inwardly projecting annular flange on the open end of the inner tube, a disk peripherally smaller than and arranged within the opening formed by said annular flange, and a projecting stop and co-acting segmental recess between the 65 coinciding peripheries of said disk and flange; and means to maintain said elements in operative register, consisting of an interiorly arranged flanged disk abutting against the inturned flange of the inner tube, with means 70 to maintain said coinciding elements in fixed relation to each other and to a buffer head.

In testimony whereof, I have hereunto affixed my signature this fourth day of October A. D. 1906.

MARION B. RIFFO.
